UNITED STATES PATENT OFFICE.

VERNON A. GARDNER, OF ANGIER, NORTH CAROLINA.

CLOTHES BOILER.

Application filed July 11, 1923. Serial No. 650,943.

My present invention has reference to clothes washing apparatus.

My object is to produce a clothes washing machine of a construction whereby boiling water will be forced in spray-like streams against the clothes to cause a continuous agitation thereof and thereby clean the clothes in a quick and efficient manner without liability of injury to the finest fabrics.

10 A further object is to produce a clothes washing apparatus that includes a clothes receptacle having a heating chamber therebelow, said chamber being surrounded by a water drum, while communicating with the bottom of the chamber and depending into the heating chamber there is a plurality of spur tubes, the water from the clothes receptacle being conveyed into the drum and into the spur tubes and heated to a boiling point 15 so that the boiling water therefrom will continuously rise and force itself into the clothes receptacle to act upon the clothes arranged therein and by the agitation thus imparted, the clothes will be thoroughly 20 cleaned in a quick and effective manner.

A still further object is to produce a clothes cleaning apparatus in which boiling water is continuously injected into a chamber in which the clothes to be cleaned are 30 placed and which shall embody the desirable features of simplicity and cheapness in construction, together with thorough efficiency in operation.

A still further object is to produce a 35 clothes washing apparatus in which a clothes receptacle has a heating chamber therebelow, and which chamber is surrounded by a water jacket that communicates with the bottom of the clothes receptacle, said jacket 40 having its walls gradually inclined toward each other from the bottom to the top thereof whereby the said jacket is in the nature of a nozzle so that steam generated therein by the heat in the chamber will be 45 forcibly ejected therefrom on to the clothes in the receptacle, and further wherein there are provided spur tubes, also of nozzle-like constructions which communicate with the bottom of the clothes receptacle and depend 50 into the heating chamber.

A still further object is to produce a clothes washing apparatus in which steam is injected in spray-like volumes against the clothes in a receptacle to agitate and clean 55 the same, and wherein the parts are con-

structed and reinforced in such manner as to prevent the accidental displacement, breakage or burning thereof.

To the attainment of the foregoing and other objects which will present themselves 60 as the nature of the invention is better understood, reference is to be had to the drawings which accompany and which form part of this application.

In the drawings:—

65 Figure 1 is a top plan view of my improvement.

Figure 2 is a sectional view on the line 2—2 of Figure 1.

Figure 3 is a sectional view on the line 70 3—3 of Figure 1.

Figure 4 is a bottom plan view of the improvement.

Figure 5 is a top plan view illustrating 75 a slight modification.

Figure 6 is a fragmentary plan view illustrating a further modification.

Figure 7 is a detail vertical transverse sectional view illustrating a still further and important modification.

80 Except for the floatable clothes compressing element my improvement is preferably constructed of metal or of some other suitable smooth fire resisting water holding material. In the showing of the drawings I 85 have illustrated the improvement as square or rectangular in cross section, but in manufacture I may construct my device in other shape and form.

90 Referring now to the drawings in detail, the numeral 1 designates the clothes receptacle of the improvement. The bottom of the receptacle is inclined downwardly and inwardly from its outer edge, as indicated by the numeral 2, but the bottom proper, 95 indicated by the numeral 3 is preferably straight. Preferably integrally formed at the terminal of the inclined lower corner 2 of the receptacle 1 there is a continuous depending wall 4. The wall 4 has its lower 100 edge flanged inwardly, as at 5 and is thence continued upwardly and is connected with the outer edge of the bottom 3. The last mentioned wall is, for distinction, indicated by the numeral 6. The space between these 105 walls provides a water drum which, of course, communicates with the clothes receptacle. The drum also provides an inner heating chamber 7.

110 The bottom 3, at determined, and prefer-

ably equi-distantly spaced intervals has depending therefrom and communicating therewith spur tubes 8. The tubes, of course, enter the heating chamber 7 but terminate 5 a suitable distance away from the bottom thereof.

Any desired heating medium may be employed, and the heating chamber is provided with a door 9 whose frame 10 is arranged 10 between the walls 4 and 6 of the drum. The door is preferably provided with the usual slideable draft regulating valve, and the chamber has an outlet flue 11, adjacent to its top for the products of combustion.

By reference to Figure 3 of the drawings, it will be seen that each of the spur tubes 8 has a port 12 that communicates with the water drum 13 so that water will be continuously circulated between the tubes and the drum.

In practice, a suitable amount of water, which may be mixed with the saponaceous fluid is poured in the receptacle 1 so that 25 the same enters the drum and jackets. The heater is preferably ignited so that the fluid will be heated before the clothes are placed in the receptacle. The cooler water is, of course, sustained in the receptacle, while the 30 water in the drum and tubes will be heated to a boiling point. This heated water will be forcibly ejected through the mouths of the drum and tubes on to the clothes in the receptacle 1, so that the clothes are continuously 35 agitated, and so that the clothes will be thoroughly cleaned in an automatic and expeditious manner. In order to retain the clothes close to the bottom of the receptacle 1, I arrange in the receptacle and over 40 the clothes a floatable top or cover 14. The cover is preferably constructed of spaced longitudinally arranged slats connected by transverse elements which may be also in the nature of slats. The cover has a central handle 15 whereby the same may be 45 readily removed or arranged in the receptacle as desired. The cover is of sufficient weight to influence the clothes toward the bottom of the receptacle.

As the drum and the tubes are filled with water during the washing process the liability of these parts being affected by the heat in the heating chamber is reduced to a minimum, if not entirely overcome, but the 50 depending water tubes may have a tendency to be warped by such heat. To overcome this, I secure to the inclined lower corner 2 of the receptacle both on its inner and outer faces, straps 16, as clearly illustrated in Figure 2 55 of the drawings. These straps are bent and continued against the inner and outer walls of the drum, over the bottom 3 of the clothes receptacle and against the inner and outer as well as the bottom walls of the 60 spur tubes 8. The straps are secured in any

desired manner but the securing means is such as to not permit of the leakage of water therethrough. The water drum has at its bottom an outlet cock 17, whereby the water from the drum, receptacle and tubes 70 may be drained as occasion requires.

In Figure 5 of the drawings, the construction is substantially similar to that above described, except that the mouths of the water drum and spur tubes do not open into 75 the bottom of the receptacle, the bottom 18 of the clothes receptacle 19 being provided with series of apertures 20 and 21 which communicate respectively with the drum and with the spur tubes. With this construction the apertures provide outlet nozzles for the heated water and steam from the drum and spur tubes so that the said fluid will be forced against the clothes in 80 divided sprays.

In Figure 6, the device is also substantially similar to that previously described, the water drum 22 communicates directly with the bottom of the receptacle, but the bottom is not provided with the spur tubes. 90 In lieu of the spur tubes there are depending from the bottom and, of course, communicating therewith, spaced series of pipes 23, the said pipes being connected together at their lower ends by a transversely arranged pipe 24, and this last mentioned pipe is let in one of the sides of the water jacket 22. In operation, the hot water and steam from the pipes are ejected in nozzle-like 95 sprays, while the hot water and steam from the drum 2 is forced against the clothes in 100 a continuous volume.

In Figure 7, I have illustrated an important modification. In general, the construction is also similar to that above described, but the inner and outer walls 25 and 26 of the water drum 27 are arranged at a gradual inward angle with respect to each other so that the mouth of the drum 27 is restricted at its communication with 105 the clothes receptacle. Also in the said figure, the spur tubes 28 have their side walls gradually inclined toward each other to provide restricted mouths 29 that communicate with the clothes receptacle 30. In this instance, both the water drum and the spur tubes are in the form of spray nozzles so 110 that the heated water and steam will be violently forced therefrom in a continuous spray against the clothes in the receptacle 30.

From the foregoing description, when taken in connection with the drawings it will be seen that I have produced an automatic clothes washer which is of an extremely simple construction and which may be cheaply manufactured and marketed. The device is light in weight so that the same may be conveyed to different places in a laundry or the like. If desired, the 125 130

bottom of the improvement may have casters arranged thereon to facilitate the movement of the machine.

It is believed that the foregoing description, when taken in connection with the drawings, will fully set forth the construction, operation and advantages of my improvement, but I desire it understood that I do not hold myself restricted to the structural details herein set forth and that I may make all such changes therefrom as fairly fall within the scope of what I claim.

Having described the invention, I claim:—

15 A wash boiler comprising a clothes receptacle having its corners flared inwardly at the closed bottom thereof and provided

at the terminal of the said flared portion with a water drum whose side walls are inclined away from each other to the closed 20 bottom thereof to provide a restricted communication with the receptacle, said receptacle having depending from its bottom, inward of the drum, spur tubes, each having its side walls inclined outwardly to the 25 closed bottom thereof to provide restricted openings which communicate with the receptacle, and said spur tubes terminating a distance above the bottom of the drum, and the drum, below the spur tubes providing 30 a combustion chamber.

In testimony whereof I affix my signature.

VERNON A. GARDNER.
